UNITED STATES PATENT OFFICE.

CLARK S. EVANS, OF OAKLAND, CALIFORNIA.

OIL-BURNER.

No. 878,874.

Specification of Letters Patent.

Patented Feb. 11, 1908.

Application filed July 24, 1907. Serial No. 385,310.

To all whom it may concern:

Be it known that I, CLARK S. EVANS, citizen of United States, residing at Oakland, in the county of Alameda and State of California, have invented new and useful Improvements in Oil-Burners, of which the following is a specification.

My invention relates to oil burners. Its object is to provide a simple practical oil burner especially designed for use on locomotives or other places where there is a variable draft due either from starting or stopping the engine, or from other causes.

It has other objects, which, together with the advantages claimed therefor, will be more fully apparent hereinafter.

The invention consists of the parts and the construction and combination of parts as hereinafter more fully described and claimed, having reference to the accompanying drawings, in which—

Figure 1 is a longitudinal section of my burner. Fig. 2 is a section on X—X, Fig. 1. Fig. 3 is an end view of the burner showing the flame adjustment.

A represents an outer shell or casing having a tapered interior larger at the rear end and adapted to receive a plug 2; the plug 2 and the inside of the rear end of the casing 30 being ground to have a snug turning fit. Preferably the outer casing is of iron or steel and the plug 2 of a different metal, as brass. The plug 2 is adapted to project a short distance outside the casing A, and is removably held thereto by suitable means, as the screw-cap 3. The plug has a central stem extending through the cap 3, and to which stem, at 4, may be attached an operating handle. Suitably secured to or cast integral with the 40 front end of the plug 2 is a pipe 5, which extends forward concentric with the shell A, and has a flared end 6 terminating flush with the forward end of the shell A and spaced therefrom to form a contracted annular discharge orifice.

The plug 2 has a steam inlet port 7 which is in continuation of the passageway in the pipe 5, and which port is adapted to register with an inlet 8 through the casing, and to 50 which inlet the steam pipe 9 is attached. Outside the port 7 is a recess or depression 10 in the plug which is adapted to bring the oil pipe 11 into register with the annular space 12 inside the burner when the plug is turned 55 into operative position.

As will be seen from Fig. 2, the oil port 10 is narrower than the steam inlet port 7, so that in turning the plug to turn on the steam and oil to the burner, the steam port 8 will be uncovered before the oil port is uncovered. 60 The purpose of this construction is to insure the blowing out of all the water of condensation before the oil is admitted to the burner, when starting up the burner, and to insure the cutting off of the oil before the steam is 65 cut off, when shutting down the burner.

In operation, the parts being assembled and suitably connected with the steam and oil pipes, the oil and steam are turned on, as just described, by a simple operation of the 70 lever handle on 4 to bring the ports 7—10 into communication with the respective pipes 9—11. The initial entry of the steam into the burner heats up the pipe 5 and blows out the water of condensation. The oil then 75 entering is in condition to be readily volatilized, and the mixture of the steam and oil takes place outside the burner and in the furnace; the resulting flame being cone-shaped, as will be manifest from the flared 80 shape of the pipe 6 and the contracted nozzle end of the casing A. Under some conditions a perfect cone-shaped flame may not be desirable or necessary, as where the top of the furnace, or the bottom of the furnace, or one 85 side or other of the furnace, may require more or less heat. I therefore provide an adjustable device by which the size and shape of the oil discharge orifice can be regulated.

As here shown, 12 represents a ring fitting 90 the end of the casing and having a depending semi-annular flange 13 projecting over one-half of the oil discharge orifice. Manifestly, this segmental flange 13 could be more or less than half a circle according to the shape and 95 size of the flame desired. The ring 12 is connected by two or more straps 14 with the ring 15, which is adapted to slip back over the burner casing, and is removably held thereto by suitable means, as the locking 100 cam 16. Since both rings 12—15 are freely turnable about the casing, it is manifest that the flange 13 can be turned to shut off the out-flow of oil from any part of the burner and restrict the flame in the furnace accordingly.

One of the principal features of this invention is its simplicity, there being only three parts; to wit, the shell, the plug with its steam pipe 5, and the retaining cap 3. 110

By having the plug and steam pipe mounted for oscillation, and the plug being ported as described, this plug acts as a controlling valve for both the steam and the oil, and 5 therefore the burner is a single valve burner.

The length of the plug is sufficient to allow for take-up by the cap 3. No stuffing boxes are necessary, either, in this burner.

It is not necessary to have any extra fittings whatsoever to blow out or clean out 10 this burner, as it will clean itself, by simply turning the oil port in the valve into line with the steam inlet pipe; and in so doing the steam enters the oil compartment or 15 shell of the burner and blows all sediment or refuse out the nozzle of the burner.

This burner will not smoke, with the proper draft, and it can be used as a gravity or a 20 force feed burner with perfect satisfaction; it is an oil saver, and can be used on any 25 boiler using oil as a fuel.

It is a direct-acting, single-valve burner, oil and steam being admitted through the same valve without coming in contact with 25 each other until reaching the furnace.

Having thus described my invention, what I claim and desire to secure by Letters Patent is—

1. In an oil burner, the combination of a 30 casing, a unitary plug turnable in the casing, said plug having an oil inlet port and a separate steam inlet port, said plug having a longitudinally extending steam passage and said casing having a longitudinally extending 35 oil passage concentric with said steam passage, and said plug being turnable to regulate the admission of both the steam and oil to the burner.

2. In an oil burner, the combination of a 40 shell open at both ends, said shell having a conical bore, a single plug seating in and turnable in the bore, said plug having separate oil and steam ports registerable with corresponding ports in the casing, said plug 45 having a longitudinally extending steam passage and said shell having a longitudinally extending oil passage concentric with said steam passage, said plug being turnable to regulate the admission of both the steam 50 and oil.

3. In an oil burner, the combination of a 55 casing having a conical bore, a plug turnable in the bore, a cap for retaining the plug in position, said plug having separate steam and oil ports registerable with corresponding ports in the casing, said plug having a forward hollow extension within the casing and

concentric therewith and in continuation with said steam port, said extension having a flared end terminating approximate to the 60 front end of the casing and coöperating therewith to form an annular oil outlet.

4. In an oil burner, the combination of a casing having a conical bore, a plug turnable in the bore, a cap for retaining the plug in 65 position, said plug having separate steam and oil ports registerable with corresponding ports in the casing, said plug having a forward hollow extension within the casing and concentric therewith and in continuation 70 with said steam port, said extension having a flared end terminating proximate to the front end of the casing and coöperating therewith to form an annular oil outlet, and means including a rotatably mounted 75 segmental flange overlapping the end of the burner to regulate the oil discharge.

5. In an oil burner, the combination of a casing having a conical bore, a plug turnable in the bore, a cap for retaining the plug in 80 position, said plug having separate steam and oil ports registerable with corresponding ports in the casing, said plug having a forward hollow extension within the casing and concentric therewith and in continuation 85 with said steam port, the front of the extension being flared outwardly and terminating proximate to the front end of the casing said steam port in the plug arranged upon turning the plug to admit steam into the 90 burner prior to the entry of the oil therein.

6. The combination of a casing member having a conical bore, a plug turnable in said bore said plug having a longitudinally extending steam passage and said casing having a longitudinally extending oil passage 95 concentric with the steam passage, and said plug having two separate inlets registerable with two corresponding separate and distinct fluid inlets in the casing, the forward 100 end of the steam passage in the plug flaring outwardly toward and terminating proximate to the front end of the casing, one of said inlets adapted upon turning the plug to open prior to and to close subsequent to the opening and closing of the other inlet.

In testimony whereof I have hereunto set my hand in presence of two subscribing witnesses.

CLARK S. EVANS.
